UNITED STATES PATENT OFFICE.

FREDERICK WILLIAM WOOD, OF LONDON, ENGLAND, ASSIGNOR TO LINOTYPE AND MACHINERY LIMITED, OF LONDON, ENGLAND.

PRESS FOR EMBOSSED PRINTING.

981,346.

Specification of Letters Patent. Patented Jan. 10, 1911.

Application filed June 25, 1909. Serial No. 504,291.

To all whom it may concern:

Be it known that I, FREDERICK WILLIAM WOOD, a subject of the King of the United Kingdom of Great Britain and Ireland, and residing at 188 and 189 Fleet street, in the city of London, England, have invented new and useful Improvements in Presses for Embossed Printing, of which the following is a specification.

10 The invention relates to power-driven presses for embossed printing, of the type in which a downwardly-presented die is caused to travel first over a device from which it receives its charge of ink, and then over another device which wipes its under surface to remove the superfluous ink therefrom, and in which it is thereafter brought beneath a spring- or equivalently depressed plunger which when released and allowed to descend, causes the impression to be made; after the blow is struck, the plunger is raised to and locked in, its highest position ready for its next release for making the next embossing stroke.

25 A press of the just mentioned type is fully described in the specification forming part of Letters Patent No. 677223 dated June 25th, 1901, and it is to that particular construction of press that the present improvements are applicable, the object of this invention being to provide means for enabling the operator, while stationed at the front of the press, to exercise more efficient control thereover, than has hitherto been possible with presses of the same type.

In the accompanying drawings which are to be taken as part of this specification and read therewith:—Figure 1 is a perspective view of sufficient of a press to show the application thereto of the present improvements; Fig. 2 is an elevation, as seen from the right-hand side of the press, showing the wiping-paper feed mechanism, which latter is represented as partly broken away; Fig. 3 is a front elevation of part of the press showing means according to these improvements controllable by the operator for arresting the descent of the die; Fig. 4 is an elevation and Fig. 5 a vertical section about on the line 7—7 of Fig. 4, of part of the mechanism shown in Fig. 5; and Fig. 6 is a diagrammatic section taken about on the line 8—8 of Fig. 3, illustrating certain

parts of the mechanism for raising, locking and releasing the press plunger. 55

It is sometimes found necessary to feed the wiping paper 19, (shown in dot-and-dash lines in Fig. 2) onward while the press is not at work, and for this purpose the operator has hitherto been compelled to leave 60 his position at the front of the press, remove the pressure pad 20 out of contact with the wiping paper, and then, from a position difficult of access at the back of the press, turn, by hand, the feed roller 21 and take-up 65 roller 22, all of which absorbs a considerable amount of time and moreover is responsible for loss of ink because the pressure of the pad 20, having been removed from the back of the paper 19, the 70 scraping knife 23 cannot efficiently scrape the ink from the paper then moved past it.

The feed roller 21^a which co-operates with the before-mentioned feed roller 21 and the take-up roller 22, during the normal working 75 of the press, are caused to rotate by means of a vertically reciprocated rack bar 24, which, as ordinarily, is depressed by a cam (not shown in the drawings) and raised by a spring 25 and which rack bar, as usual, 80 imparts rotary motion to the rollers 21^a and 22 through the ratchet devices 26, 27 respectively; it is this said rack bar 24, which, according to the present invention is utilized for operating the rollers 21^a, 22 at the 85 will of the operator. For this purpose the rack bar 24 is adapted to be depressed by a foot lever 28 pivoted at its rear end to a fixed bracket 29 and having its forward end situated so as to be convenient for depression by the foot of the operator when 90 stationed at the front of the press. The engagement of the lever 28 with the rack bar 24 may be by way of a pawl pivoted on the former engaging a tooth or recess on the latter, or preferably, as shown in Figs. 1 and 2, by a stud or abutment 30 fast to the rack bar 24 permanently projecting laterally therefrom, into the path of the lever 28. A stop 31 is provided for limiting the upward movement of the lever 28, and a spring 32, or the equivalent thereof, may be provided for returning the said lever up to this stop, after it has been released by the operator. 100

During the normal working of the press,

the rack bar 24 fulfills its ordinary function, and during the non-working of the press the said rack bar, when desired, is caused to effect the same operation by the 5 depression of the foot lever 28, and this without the pressure pad 20—and consequently the efficiency of the ink scraper 23—being interfered with in any way.

In the case of failure to feed a sheet into 10 the position in which it receives the impression, and for other reasons, it, sometimes, becomes necessary to prevent the descent of the die so as to avoid the inking of the counterpart and possibly injury to the press or operator. The only provision which has heretofore been made for dealing with such contingencies is the ordinary clutch lever 48 by means of which the operation of the press, as a whole is arrested, but these means can 15 not be depended upon for preventing the descent of the die-depressing plunger unless the said clutch lever is actuated considerably in advance of the time at which such descent is due. As, however, the necessity for preventing the descent of the plunger is sometimes not recognized until the latter is just about to descend, many attempts to prevent this descent by means of the clutch lever, prove futile. According to the present invention 20 this difficulty is entirely overcome by means of a manually controllable pawl 33, which is additional to the pawls 55 described in the before mentioned specification of Letters Patent No. 677,223, and one of which 25 pawls 55 is shown in Fig. 1, the said pawl 33 being adapted to engage with one of the racks 50 with which the pawls 55 engage. This additional pawl 33 is free to turn upon a stationary stud 34 fast in a yoke or bracket 30 35 rigidly secured to the drumhead casing 36. The pawl 33 is held in either its effective or ineffective position by a spring 37 attached at its upper end to the said pawl and at its lower end to a pin 38 fast to an arm 39 pivoted on the stud 34. The pin 38 engages with a slot 40 in one arm of a bell-crank lever 41 pivoted at 42 to the yoke or bracket 35, and the other arm of which is connected through a link 43 with a hand 45 50 lever 44 pivoted at 45 to the main frame of the press.

When the hand lever 44 is in its raised or normal position in which it is diagrammatically represented by a dot-and-dash line in 55 Fig. 3, and the arm 39, in consequence thereof, is substantially in line with the pawl 33 as diagrammatically represented by the dot-and-dash line in Fig. 4, the pawl 33 is, by the pull of the spring 37, held out of the 60 path of the appropriate rack 50, and when the said hand lever is in the lower position in which it is shown in full lines in Fig. 3, and, in consequence thereof, the arm 39 is situated at an angle to the pawl 33 also as 65 shown in full lines in Figs. 3 and 4, the said

pawl, by the pull of the spring 37, is held in the path of the rack 50 and thereby capable of engaging with the latter and preventing the descent of the die-depressing plunger 46 Fig. 1.

As described in the specification of the before mentioned Letters Patent the plunger 46 is screw-threaded and threaded through a nut, its ascent and descent being effected by turning it about its axis in respectively 70 opposite directions. The rotation of the plunger 46 in the direction necessary for effecting its ascent, is effected by the devices shown in the accompanying Fig. 8 which is practically identical with Fig. 15 of the 75 drawings of the before mentioned Letters Patent. In this arrangement there is secured on the plunger 46, within the drum-head casing 36, an arm 51 adapted to move with the plunger throughout its entire angular motion and having pivoted to its free or outer end a connector or link 52 which is furnished with a drag roller 53, a locking roller 54 and a larger or cam roller 155, the three rollers being arranged triangularwise. 80

Secured upon a ledge within the casing 36 is a guide 56 and upon the plunger 46 there is free to rotate a cam-arm 57 operatively-fast to a cam or tripping piece 58, the two parts 57 and 58, during the normal working 95 of the press, constantly rotating as one entity upon, and independently of, the plunger. During the rotation of the cam arm 57, its forward edge comes into contact with the drag-roller 53, and so drags along with it 100 the link 52, which, through the arm 51, turns the plunger 46 about its axis in the direction which causes it to ascend and the springs 59 to be compressed. At or about the termination of this same rotation of the cam-arm 105 57, the roller 155 comes into contact with a fixed cam plate 60 which causes the free end of the link 52 to be deflected outward so as to cause the locking roller 54 to roll into a recess 61 formed in the end of the guide 56, 110 and the drag roller 53 to be disengaged from the cam-arm 57, the formation of the recess 61 being such that the locking roller 54 is retained therein after the cam-arm 57 has passed out of contact with the roller 53. The 115 plunger 46 is thus locked in its raised position, with the springs 59 compressed and ready to rotate the plunger in the direction necessary for causing it to give the impression blow.

The release of the plunger 46 is effected by the cam or tripping piece 58 coming into operative contact with the outer side of the cam roller 155 and thereby drawing the locking roller 54 inward out of the recess 61 125 and thus allowing the springs 59 to turn the plunger and force it downward. Consequent upon the force of the impact the plunger 46 rebounds and in doing so the teeth of the racks 50 slip over the respec- 130

tive pawls 55 which, at the termination of such rebound, engage with the said racks and maintain the plunger in its partially raised position, the completion of the plunger's ascent being effected by the devices hereinbefore described and shown in Fig. 8. The pawl 33 is so situated that it will allow the appropriate rack 50 to return to the extent of about half the length of one of its 10 teeth, after the said rack has reached the limit of its upward stroke, this provision being desirable in order that at such extreme limit the pressure may be removed from the pawl 33 to enable the latter to be easily 15 lowered by the operator out of the path of the said rack for allowing the plunger 46 to be again depressed. Suitable means may be provided for temporarily retaining the hand lever 44 in either of its two terminal 20 positions, for example, a plunger or projection may be provided on the hand lever 44, adapted to engage with depressions on a stationary sector 47.

I claim:—

25 1. In a press for embossed printing, the combination with a plunger adapted to deliver the embossing blow, a spring adapted to cause the plunger to deliver the said blow, means adapted to automatically raise the 30 plunger against the action of the spring and to arrest the plunger in its elevated position, and a device adapted to automatically release the plunger, of means under the control of the operator adapted to arrest the 35 descent of the plunger after it has been released by the automatic arresting means.

2. In a press for embossed printing, the combination with a plunger adapted to deliver the embossing blow, a spring adapted 40 to cause the plunger to deliver the said blow, means adapted to automatically raise the plunger against the action of the spring and to automatically arrest it in its elevated position, a device adapted to automatically release the plunger, and racks and a pawl 45 device adapted to automatically arrest the plunger after its rebound, of a pawl adapted to be moved by the operator into operative relationship to one of the racks for the

purpose of arresting the descent of the plunger after the latter has been released from the control of the automatic arresting means 50

3. In a press for embossed printing, the combination with a plunger adapted to deliver the embossing blow, power means 55 adapted to cause the plunger to deliver the said blow, means adapted to automatically raise the plunger against the action of the power means and to arrest it in its elevated position, a device adapted to automatically release the plunger, racks and a pawl device adapted to automatically arrest the plunger after its rebound, and a pawl adapted to be moved into and out of operative relationship to one of the racks, of a spring in operative 60 connection with the pawl adapted to hold it in the said relationship, and devices at the front of the press operatively connected with the pawl whereby the operator can move the said pawl into and out of the said 65 relationship.

4. In a press for embossed printing, the combination with a plunger adapted to deliver the embossing blow, power means adapted to cause the plunger to deliver the 75 said blow, means adapted to automatically raise the plunger against the action of the power means and to arrest it in its elevated position, a device adapted to automatically release the plunger, racks, and a pawl device 80 adapted to automatically arrest the plunger after its rebound, and a pawl adapted to be moved into and out of operative relationship to one of the racks, of a pivot for the pawl, an arm pivoted and capable of angular movement on the said pivot, a spring in operative connection at one end with the pawl and at the other end with the free end of the arm, and devices at the front of the 85 press operatively connected with the arm 90 whereby the operator can turn the latter on the pivot independently of the pawl.

In witness whereof I have hereunto set my hand in the presence of two witnesses.

FREDERICK WILLIAM WOOD.
